UNITED STATES PATENT OFFICE.

FRANK H. SKINNER, OF CHICAGO, ILLINOIS.

PIN-PULLER.

1,072,521.

Specification of Letters Patent.

Patented Sept. 9, 1913.

Application filed February 3, 1912. Serial No. 675,299.

To all whom it may concern:

Be it known that I, FRANK H. SKINNER, a citizen of the United States, residing at Chicago, in the county of Cook and State 5 of Illinois, have invented certain new and useful Improvements in Pin-Pullers, of which the following is a specification.

My invention relates to dental instruments and its object is to provide still further improvements in pin pulling devices 10 heretofore invented by me for the purpose of removing crown-pins from the roots of teeth that have been crowned.

One of the principal objects of the present improvement is to provide a form of construction that will materially reduce the cost of manufacture, and that will make it possible to stamp the body of the instrument out of sheet metal.

Another object of the invention is to place the jaw-actuating screw, which is near the root of the tooth to be operated upon, outside of the plane of movement of the jaw, thereby giving the operator a better accessibility to the screw in turning it.

Further objects are a light and neat construction, independence of each jaw so that one jaw may be repaired or replaced without discarding the whole instrument, and a 30 larger opening movement of the jaws by mounting both on pivots on which they may be swung away from each other to any desired extent.

With the above-named objects in view, and such other advantages as may appear from the subjoined description, my invention consists in the novel construction, combination and arrangement of parts herein-after described in detail, illustrated in the accompanying drawing and incorporated in the appended claims.

In the drawing—Figure 1 is a perspective view of a substantially full-sized instrument embodying my invention. Fig. 2 is an enlarged side elevation. Fig. 3 is a vertical section.

In the several views the post-actuating screw and the jaws are mounted on a cross-bar having a central nut-portion 2 and hinge-knuckles 3 and 4. A post-actuating screw 5 has threaded engagement with the nut-portion 2 and is provided with a thumb-piece 6. On the knuckles 3 and 4, in slots 7 and 8 thereof, are pivoted a pair 50 of sheet-metal jaws 9 and 10 which have inwardly bent beaks 11 and 12 with

serrated faces as shown in Fig. 3. On the inner end of the screw 5 is swiveled a forked post consisting of a strip of metal bent upon itself to form prongs 13 and 14. 60 These prongs are supported upon each other to prevent their spreading apart near the beaks of the jaws, by a bridge-piece or rivet 15. On the jaws are struck-out ears 16 and 17, the former forming a stop 65 against which a shoulder 18 of a screw 19 bears. This screw has a reduced threaded portion 20 which has threaded engagement with the ear 17. A thumb-piece 21 completes this screw. 22 and 23 are the pivots upon 70 which the jaws swing, and 24 is the swivel-connection between the screw 5 and the post. A root of a tooth to be operated upon is represented by dotted lines in Fig. 2 and a pin 26 cemented into said root and 75 about to be withdrawn by the instrument is shown in the grip of the beaks of the jaws which have been clamped upon the pin by turning the screw 19.

In operation the projecting portion of the crown-pin 26 is withdrawn by turning the screw 5 to advance the post or prongs against the root 26. The jaws thus effect a pulling strain upon the pin while the post pushes against the root. In this manner the crown-pin may be removed without subjecting a patient to any pain or strain.

I claim as my invention—

1. In a pin puller, the combination with a cross-bar, of a pair of jaws pivotally mounted in said cross-bar, a post co-operating with said jaws, a screw having threaded engagement with said cross-bar and swiveled to said post, and a screw actuating said jaws.

2. In a pin puller, the combination with a cross-bar of a pair of jaws pivoted to the ends of said cross-bar, a screw having threaded engagement with said cross-bar intermediate of said jaws, a post movable by said screw, and means operable laterally of the plane of movement of said jaws for actuating said jaws.

3. The combination with a cross-bar, of a pair of jaws, each of said jaws hinged to said cross-bar, a post movable longitudinally between said jaws, a screw for actuating said post, and a screw for actuating said jaws.

4. The combination with a cross-bar, of stamped-out sheet metal jaws pivoted to said cross-bar, said jaws having integral

bent out portions forming ears to be engaged by a screw, a screw having threaded engagement with one of said ears and having a shoulder bearing against the other of said ears, a longitudinally movable post, and a screw swiveled to said post and having threaded engagement with said cross-bar.

5. The combination with a cross-bar, of a pair of sheet-metal jaws hinged to said cross-bar, a post bent upon itself and having prongs which engage both sides of the

beaks of said jaws, a screw swiveled to said post and threaded into said cross-bar, and a screw arranged at one side of said jaws 15 for actuating same.

In testimony whereof I have hereunto set my hand in the presence of two subscribing witnesses.

FRANK H. SKINNER.
